(57) **CLAIM**

The ornamental design for a bottle caddy, as shown and described.

DESCRIPTION

FIG. 1 is front, side perspective view of the bottle caddy according to the present invention shown in an open position;

FIG. 2 is a front elevation view thereof shown in a closed position;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The strap shown in FIGS. 3–7 is shown broken away for clarity of illustration and to indicate indeterminate length. The broken lines shown on the bottle caddy are understood to represent stitching.
